Primary Examiner — Jonathan J Han*Assistant Examiner* — Caitlin Mackenzie Williams(74) Attorney, Agent, or Firm — Banner & Witcoff, Ltd.(57) CLAIM

The ornamental design for a shoe as shown and described.

DESCRIPTION

FIG. 1 is a front perspective view of a shoe showing my new design;

FIG. 2 is a side view thereof; and,

FIG. 3 is a rear perspective view thereof.

The even-length broken lines represent stitching that forms no part of the claimed design. The eight uneven-length broken line circular regions within the shaded area represent eyelets that form no part of the claimed design. The uneven-length broken lines depicting the remainder of the shoe form no part of the claimed design.
